UNITED STATES PATENT OFFICE.

FRANCIS M. UNDERHILL, OF NEW YORK, N. Y., ASSIGNOR TO WIIITALI,
TATUM & CO., OF SAME PLACE.

DESIGN FOR A BOTTLE.

SPECIFICATION forming part of Design No. 27,292, dated July 6, 1897.

Application filed May 25, 1897. Serial No. 638,172. Term of patent 14 years.

To all whom it may concern:

Be it known that I, FRANCIS M. UNDERHILL, a citizen of the United States, residing in the city, county, and State of New York, 5 have invented and produced a new and original Design for a Bottle, of which the following is a specification.

The leading feature of my design is a ribbed bottle of a general globular form, but having 10 substantially straight sides, with a ring or band at or about its middle. A bottle embodying my design is shown in the accompa-

nying drawings in side elevation in Figure 1 and in plan in Fig. 2.

In the drawings, A is a globular banded 15 bottle having the band b encircling its middle and provided with a projecting neck c.

What I claim is—

The design for a bottle, substantially as shown.

FRANCIS M. UNDERHILL.
